UNITED STATES PATENT OFFICE.

JOSEF GEIGER, OF AUGSBURG, GERMANY, ASSIGNOR TO MASCHINENFABRIK AUGSBURG-NUERNBERG, A CORPORATION OF GERMANY.

ARRANGEMENT OF INTERNAL-COMBUSTION ENGINES ON LOCOMOTIVES.

Application filed May 22, 1923, Serial No. 640,802.

To all whom it may concern:

Be it known that I, JOSEF GEIGER, a citizen of the German Republic, and resident of Augsburg, Bavaria, Germany, have invented certain new and useful Improvements in the Arrangement of Internal-Combustion Engines on Locomotives, of which the following is a specification.

In the employment of internal combustion engines on high power locomotives great difficulties are usually encountered in suitably accommodating engines of the required size within the restricted space which is at disposal upon such locomotives. This is especially the case when the engine has to be placed co-longitudinally with the locomotive, as then only the room above the axles of the car up to the top boundary line as given by the height of the car frame could be used.

The invention, now, provides for an arrangement which enables the installation, on locomotives, of lengthwise disposed engines of considerably larger size than has been heretofore possible. The increase in height according to the invention amounts to as much as approximately half the length of the engine stroke so that engines of considerably larger output may be installed.

According to the invention the engine is so arranged that its cranks are disposed within the space between the driving axles of the locomotive, it being only necessary, for the purpose, to make the distance between the said axles equal to a whole figure multiple of the distance between each two engine cylinders. The base plates upon which the engines are usually mounted and upon which the crank shafts are journalled may be dispensed with and the engine suspended in standards. At the bottom the engine may be closed up by a sheet metal lagging.

If correspondingly large driving wheels are used for the locomotive, the arrangement according to the invention will permit of disposing the crank shaft below the driving axles and to thereby effect an additional gain in the height of the available engine room.

Further advantages of the arrangement according to the invention are the location of the centre of gravity very low down in the car, a considerable saving in weight and material owing to the omission of the base or foundation plate, and an improved ac-

cessibility of the crank shaft, the bearings and the working parts of the engine from below, as only the sheet metal lagging has to be removed in order to render these parts accessible from the working pit. The crank shaft, being suspended, may be removed from below in a most simple manner without having to dismantle the engine.

The accompanying drawing diagrammatically illustrates the invention by way of example.

Fig. 1 is a part sectional side elevation of a portion of a motor locomotive.

Fig. 2 is a cross section of Fig. 1 taken through one of the main bearings and the driving wheels of the car, parts being shown in elevation.

In this drawing 1 denotes the cylinder and 2 the piston of a multi-cylinder Diesel engine disposed lengthways within a motor locomotive. The crank shaft 3 is journalled in main bearings 4 which are suspended in standards 5. Sheet metal laggings 6 serve to close the crank case at the bottom. It is evident from the drawing, that in an arrangement according to the invention the distance *a* between the driving axles of the locomotive must be a whole figure multiple of the distance *b* between the cylinders. In the example shown it is three times that distance. The bearing brasses 7 within which the crank pins are carried are connected to the standards 5 by means of strong bolts 8, and in order to compensate for wear in the main bearings, the top brasses 9 are made adjustable by the interposition of wedge pieces 10 between the said brasses and the standards.

What I claim is:—

1. The combination with a locomotive having a plurality of axles, of a multi-cylinder internal combustion engine mounted lengthwise of the locomotive and having its crank shaft supported in bearings, certain of which lie in vertical planes, passing through the locomotive axles, whereby its cranks ply in the spaces between said axles.

2. In a motor locomotive in which the internal combustion engine is arranged co-longitudinally with a multiple cylinder locomotive, means to suspend the crank shaft directly above the axles of the locomotive so as to permit of the cranks plying into the space between the said axles.

3. In a motor locomotive in which a mul-

multiple cylinder internal combustion engine is arranged co-longitudinally with the locomotive, the arrangement whereby the distance between the driving axles of the locomotive ⁵ is a whole figure multiple of the distance between each two engine cylinders.

4. In a motor locomotive in combination with a multiple cylinder internal combustion engine arranged co-longitudinally with the locomotive, standards to suspend the crank shaft directly above the axles of the locomotive without requiring the use of a foundation plate and so as to permit of the ¹⁰ cranks plying into the space between the ¹⁵ said driving axles.

5. The combination with a locomotive having a plurality of coupled axles, of a multi-cylinder internal combustion engine mounted lengthwise of the locomotive above the axles and having its crank shaft mounted in ²⁰ bearings suspended in standards, certain of these bearings lying in vertical planes passing through the locomotive axles, and the shaft being so supported that its cranks ply in the spaces between said axles. ²⁵

In witness whereof I affix my signature.
J. GEIGER.
